United States Patent Office

Des. 199,787
Patented Dec. 15, 1964

199,787

CHAIR OR SIMILAR ARTICLE

Nicholas S. Katselianis, Chicago, Ill., assignor to Emil J. Paidar Company, Chicago, Ill., a corporation of Delaware

Filed Aug. 27, 1962, Ser. No. 71,457

Term of patent 14 years

(Cl. D15—1)

The dominant features of my design reside in the portions shown in full lines on the drawings. The portions not shown are substantially plain.

I claim:

The ornamental design for a chair or similar article, as shown and described.
